DISKING DEVICE

Fred M. Hargrave, Cedar Rapids, Iowa

Application November 23, 1936, Serial No. 112,201

7 Claims. (Cl. 37—145)

This invention relates to grader planers or disking machines and has particular relation to means for attaching a disking device to a supporting and actuating structure such as a grader, 5 a motor patrol or the like.

It has been found that disking means, such as a plurality of concavo-convex disks, may be advantageously employed in connection with graders and like structures for smoothing, scarifying, mixing and planing road surfaces and for cutting and disking earth and the like as set forth in my Patent No. 1,996,676, granted April 2, 1935.

Disking devices of this character have been employed in connection with graders in which a scraper blade or mold board is suspended beneath the machine by means of a blade supporting structure including a roughly triangular framework which is adapted to be raised and lowered to raise and lower the blade and a "circle" or a "bull ring" which permits the blade to be rotated to various positions for "sidecasting" material to one side or the other and for pushing the material straight ahead, as in scraping or bulldozing operations.

In my patent above noted I have provided a disking means including a plurality of concavo-convex disks which are so supported and mounted in a unit that they may be substituted for the scraper blade whereby the grader may be used for disking operations.

I have found it very desirable, however, that the disking means be mounted on the supporting mechanism in such manner that the disking means may be used without removing the scraper blade, and such that the disking means may be drawn up out of the way to permit the scraper blade to be used without dismounting the disking means, and it is accordingly a general object of my invention to provide mounting means of this character.

In practicing my invention I preferably provide a standardized disking mechanism and then provide several fastening members which may be used interchangeably for fastening the disking means to the grader or like structure in several positions in front of and in back of the mold board of the grader. One set of fastening means is adapted to support the disking means from the circle hangers or "ram's horns", which supports the mold board, and another set of fastening means is adapted to support the disking means from the circle. The mounting of the disking means in these several positions constitute some of the general objects of my invention.

It is another general object of my invention to provide a new and improved means for mounting a disking means on a road grader or the like.

Another object of my invention is to provide an improved means for mounting the disking device in relation to the blade supporting framework of a grader in such manner that the grader blade may be employed without removing the disking device from the machine.

Another object of my invention is to provide an improved means for mounting the disking means on the blade supporting framework of a grader or the like.

One of the features of my invention is that the scraper blade itself may be employed as an additional stiffening means for the disking device.

Other and further features and objects of the invention will be more apparent to those skilled in the art upon a consideration of the accompanying drawings and following specification, wherein is disclosed a single exemplary embodiment of the invention, with the understanding, however, that such changes may be made as fall within the scope of the appended claims, without departing from the spirit of the invention.

Figure 1 is a view in perspective of a disking device and a mounting means therefor, as it appears when mounted on the blade supporting framework of a grader or the like. The disking means is mounted to the rear of the scraper blade and may be raised and lowered as hereinafter described.

Figure 2 is a partial view in elevation of the device shown in Figure 1 and parts of the structure have been broken away to show the remaining structure in greater detail.

Figure 3 is a fragmentary view showing a modified means of spacing the yoke member from the "ram's horns" rather than from the scraper blade as shown in Figure 1.

Figure 4 is a partial view in perspective of the disking device shown in Figure 1 and illustrates means for mounting the disking unit on the front of the scraper blade or mold board.

Figure 5 is a partial view in elevation showing the disking unit and mounting means shown in Figure 3.

Figure 6 is a view in perspective of the yoke member used for supporting the disks. This same yoke member is preferably employed in all of the structures.

Figure 7 is a view in perspective of the clamp means shown in Figures 3 and 4 for clamping

55

the yoke member to the upper edge of the mold board.

Figure 8 is a view in perspective of the disking means and means for mounting the disking unit directly on the "circle" without engaging it to the mold board, and

Figure 9 is a partial view in side elevation of the device shown in Figure 8.

Referring to the drawings and particularly to Figure 8 a "grader" or "motor patrol" structure commonly known to the art, includes a heavy framework, indicated generally at 10, and in accordance with the usual practice, this framework is supported by tandem wheels (not shown) at the front thereof and at the rear by means of a pair of drive wheels (not shown), the operator's position being approximately over the rear wheels and the motor (not shown) being mounted in front of the rear wheels and supported by the supporting framework 10.

In devices of this character a roughly triangular, blade-supporting framework, indicated generally at 11, is pivotally engaged to the frame members 10 near the front thereof and is adapted to be supported at the rear end of the triangular frame 11 and moved up and down by means of supporting members indicated generally at 12. These supporting members include screw-threaded jacks or the like, pivotally connected between the frame 10 and the blade supporting framework 11.

The supporting framework 11 is adapted to engage and support in turn a "circle" or "bull ring" 13, which is suspended beneath the framework 11, by supporting means which permit the "circle" to rotate.

Rotation of the "circle" 13 is accomplished by means of a geared circle drive indicated at 14 and the circle drive is driven by means of a shaft 16 in accordance with the usual practice.

The scraper blade or mold board 17 is supported beneath the "circle" by means of a pair of hangers or "ram's horns" 18, there being one of these horns on each side of the "circle". The mold board is pivotally engaged to the lowermost ends of the "ram's horns" by means of brackets 19, engaged to the rear of the mold board, and by pins 21, which pivotally engaged the brackets and mold boards to the lower end of the "ram's horns."

The angle of incidence of the mold board 17 may be adjusted by pivoting the mold board on the pivotal connection at 19 and 21 and it may be held in any desired position by means of slotted arms 22, which are pivotally attached to the upper rear edge of the mold board by means of brackets 23 and pins 24. The slotted portion of the arm 22 is adapted to be adjustably engaged to intermediate portions of the "ram's horns" 18 by means of bolts 26, which are passed through the slots 27 in the arms 22, and which are threaded into the "ram's horns" 18.

The structure so far described is one of the structures commonly known to the art and these devices are called by the general name of graders or road patrols. Obviously they are adapted for scraping operations only, including sidecasting of earth and snow and the like to one side or the other or pushing it ahead, which is generally termed a scraping or bulldozing operation.

It is my purpose to provide easily adjustable disking devices which may be readily attached in front of or to the rear of the scraper blade or mold board and which may be used either in conjunction with the scraper blade for disk

material before or after the scraping operation is accomplished, or which may be dropped to a level below the scraper blade and held in this position so that the road patrol may be used for various disking operations without removing the mold board from the road patrol.

I preferably employ a one-piece yoke member such as illustrated more particularly in Figure 6 for supporting the disks. This yoke member 31 is comprised of a long channel-like member 31a having roughly triangular plate members 31b and 31c at the opposite ends thereof. These plate members are additionally braced by means of U-shaped brackets 31d. The side plates 31b and 31c are provided with wide slots 31e and 31f which are adapted to receive the through shaft upon which the concavo-convex disks are mounted. The end plates 31b and 31c are provided with a plurality of openings 31g at their lower edges for a purpose to be hereinafter more particularly explained.

The concavo-convex disks 32 are mounted on a through-shaft 33 (Fig. 4) and are spaced by means of suitable spacers (not shown). The through-shaft 33 is square at that portion which engages the disks and the openings through the disks are also square in order that the disks may be caused to revolve with the shaft. The through-shaft is engaged at its ends in roller bearings, indicated at 34, and these roller bearings are supported within bearing cages 36, which are in turn mounted on the end plates 31b and 31c by means of bolts 37. It is apparent, by inspection of Figures 4 and 6, that all that is necessary in order to remove the disk assembly from the yoke member is to remove the bolts 37 and let the disk assembly and shaft 33 drop down out of the slots 31e and 31f. End play of the shaft is regulated by means of lock washer 38 in accordance with the usual practice.

I preferably utilize the disking unit just described as a standardized unit and provide various brackets and the like for mounting this disking unit in front of or in the rear of the blade and either on the blade or on the "circle" and "ram's horn" structures. The mounting means comprises substantially two types of devices, namely bracket means for pivotally engaging the yoke of the disking unit to the road grader, and link means for adjustably securing the disking unit in various positions of adjustment with reference to the scraper blade and "circle". The face of the channel member 31a is provided with two pairs of spaced bracket members 41 (see Fig. 2), which bracket members are welded in spaced relation to the channel member 31a.

In fastening the disking unit to the rear of the scraper blade, as illustrated in Figures 1 and 2, I preferably provide a pair of oppositely-disposed, roughly-triangular bracket members 42 which are provided with right angle flanges 43, the flanges 43 being adapted to be received on the rear sides of angle iron brackets 44 and 46. These bracing members 44 and 46 are used for bracing the horns 18, the angle iron 44 being a through member extending beneath the "circle" 13 and secured to it by means of oppositely disposed brackets 47.

The inner sides of the horns 18 are provided with angle iron brackets 48, which are bolted or riveted to the horns by means of rivets 51 and are also bolted or welded to the rear vertical faces of angle irons 48. The members 46 are brace members secured at their inner ends to 75

the member 44 and at the outer ends to the supports 48.

The triangular brackets 42, as previously stated, are engaged on the rear sides of the members 44 and 46, and plates 52 are provided at the front sides of members 44 and 46, the flanges 43 of brackets 42 being bolted to these plates, thus clamping the flanges tightly against the bracing members 44 and 46.

In this manner, and by means of a pivotal connection between the brackets 41 and the brackets 42, the disking unit is pivotally engaged to the ram's horns and are moved up and down. Likewise rotation of the circle will cause like rotation of the disking unit.

At times it is desirable that the disking unit be raised above the lower or cutting edge of the mold board 17 and this is accomplished by the use of clevis members 53 and spacer rods 54. The clevis members 53 are pivotally engaged at their forward ends, by means of pins 56, to brackets 57 on the rear lower edge of the mold board 17.

The clevis members 53 are hollow and are adapted to receive the rods 54. The bent ends 54a of the rods 54 are received in any of the openings 31g and the clevis members 53 and spacer rods 54 are of sufficient length that when they are in place the disking unit is held suspended with the lower edges of the disks above the cutting edge of the mold board 17. When it is desired to use the disking unit, the spacer rods 54 are removed and the clevis portions 53a of the clevis members 53 are pinned to one of each of the openings 31g, the disking unit thus being pivoted downward so that the lower edges of the disks are well below the cutting edge of the mold board 17 and the disks may thus be made to engage the surface of the ground. The disking unit may be raised and lowered and rotated at will by the same mechanism used to raise and lower and rotate the mold board.

I may mount the disking unit on the front of the mold board 17 by modified forms of brackets such as illustrated in Figures 4 and 5. The brackets 41, on the channel member 31, are the same as previously described but a modified form of bracket is used in place of brackets 42. This modified form of bracket is illustrated more particularly at 61 in Figure 7 and comprises a pair of ear members 61a, joined by a plate 61b. The ears are drilled to receive a through-bolt 62 which is received in the brackets 41 and thus the brackets 41 are pivotally attached to the disking unit. The bracket 61 is slotted, as indicated at 61c, to receive the upper edge of the mold board 17 and in engaging the bracket 61 to the mold board, the brackets are placed on the mold board with the slots 61c over the upper edge of the mold board and the brackets 61 are then locked in place on the mold board by means of set screws 63.

The means for holding the disking unit in raised or lowered position with reference to the mold board and circle is substantially the same as previously described and includes clevis members 53 in which rods 54 may be inserted. The brackets or ears 57a are placed on the front of the mold board and are a part of straps 64 which are secured to the front of the mold board, as by bolts 66, and these straps constitute means for engaging the cutting edge 65 of the mold board to the main portion 17 of the board. It is apparent that the disking device may be held in raised position by inserting the spacer rods 54 in the openings 31g and the other ends of the

rods in the clevis members 53. When it is necessary to use the disking unit, the rods 54 are removed and the clevis members directly engaged between the end plates 31b and 31c and the mold board 17.

I have illustrated, in Figure 8 and 9, a means for supporting the disking unit directly on the circle without engaging the mold board 17 and, in this structure, the brackets 41 are pivotally engaged to suitable opposed bracket members 67. These brackets 67, like the brackets 41, are secured directly to the circle. Obviously the disking device may pivot about on the brackets 41 as before. Substantially the same spacing members are utilized for holding the disking unit in raised and lowered position and these spacing means include clevis members 68 and spacer rods 69. When the rods 69 are inserted in the clevis members 68 the disking unit is supported in the position shown in Figures 8 and 9 with the lower edges of the disks above the cutting edge of the scraper blade 17. When it is necessary to use the disking unit the spacer rods 69 are removed and the clevis members 68 engaged directly in the openings 31g thereby rotating the disking unit to a position in which the lower edges of the disks are below the cutting edge of the scraper blade. If necessary the scraper blade 17 may be pivoted on the pivots 21 with the upper edge of the blade close to the horns 18 so that the cutting edge of the blade is slightly raised.

It is possible to mount the disking unit, by means of the mounting device shown in Figure 1, so that the disking unit does not engage the scraper blade at any point and this is accomplished by means of the modified structure shown in Figure 3 in which the clevis members 53a are bent in S-shape so that they engage the pins 21 instead of the pins at 56. The disking unit, as shown in Figure 1, may thus be entirely disengaged from the scraper blade and the scraper blade removed if desired.

It is apparent that I have provided a simple and easily adjusted disking unit which may be readily assembled and disassembled and that I have provided a unit of this character which may be readily attached in front of or to the rear of the scraper blade or on the circle or horns of a motor patrol or like grader device. The disking unit in all its positions of attachment, may be readily raised and lowered without the necessity of disturbing the mold board. It is apparent that modifications of my invention may be made by those skilled in the art. Such modifications may be made without departing from the spirit and scope of my invention as set forth in the appended claims.

I claim as my invention:

1. On a motor patrol, an earth moving and working device including a supporting structure, a mold board mounted on the supporting structure, a disking unit comprising a yoke member having end plates at either end thereof, the yoke member being adapted to carry the shaft of the disking device, the yoke member being provided with means for pivotally attaching it to the supporting structure and means for connecting the side portions of the end plates to the mold board, whereby the disking unit may be supported in a plurality of positions.

2. On a motor patrol, an earth moving and working device including a supporting structure, said structure including a circle, a mold board mounted on the circle, a disking device including a yoke member having end plates as a part of

- the arms of the yoke member, means for connecting the disking device to the supporting structure comprising cooperating bracket members on the yoke member and the circle, and spacing members from the end plates to the mold board.
3. In a disking device for motor patrols, a supporting structure including a circle and depending hangers, a mold board, the disking device including a yoke member and disks carried by the yoke member, and connecting means fastening the disking device to the supporting structure, said connecting means comprising bracket members adapted to connect with the hangers of the circle and spacing members adapted to rigidly connect the yoke and the mold board.
4. In a disking attachment for motor patrols, the motor patrol having a mold board mounted thereon, the said motor patrols including a circle and depending hangers on the circle, a disking device including a yoke member, clamps connected to the hangers including, reinforcing members pivotally connected to the yoke, and spacing members engaged to the end plates of the yoke member and to the lower end of the mold board.
5. In a disking attachment for motor patrols, the motor patrol having a mold board and supporting structure for same, the disking device including a yoke member and disks rotatably mounted on the yoke member, means for attaching the disking device at the rear of the mold

board comprising means for pivotally attaching the yoke to the supporting structure and spacing means attached to the rear of the mold board and to a portion of the disking device.

6. In a disking device for attachment to a motor patrol the motor patrol including a circle, ram's horns, a mold board, and reinforcing members for the ram's horns, means for attaching the disking device including brackets adapted to be engaged on the reinforcing members of the ram's horns and spacing members engaged between the disking device and the rear of the mold board.

7. In a motor patrol, an earth working device including a supporting structure, a mold board attached thereto, a disking device comprising a yoke and disks rotatably mounted within the yoke, means for pivotally attaching the yoke to the supporting structure, the ends of the yoke opposite the pivotal point having a plurality of adjustment holes, and other means including a pivotally mounted bar connected with said adjustment holes and with the mold board for spacing the disking device about its pivotal connection whereby the disking device is independently rotatable on the pivotal means to provide a plurality of positions for the disking device with respect to the supporting structure and the mold board.

FRED M. HARGRAVE. 30
